UNITED STATES PATENT OFFICE.

CHARLES A. SCHALLIS, OF PEQUANNOCK, NEW JERSEY, ASSIGNOR TO THOMAS A. EDISON, INCORPORATED, OF WEST ORANGE, NEW JERSEY, A CORPORATION OF NEW JERSEY.

DESIGN FOR A COFFEE URN OR SIMILAR ARTICLE.

Application filed October 31, 1928. Serial No. 28,707. Term of patent 14 years.

To all whom it may concern:

Be it known that I, CHARLES A. SCHALLIS, a citizen of the United States, residing at Pequannock, in the county of Morris and State of New Jersey, have invented a new, original, and ornamental Design for Coffee Urns or Similar Articles, of which the following is a specification, reference being had to the accompanying drawing, forming a part thereof.

The figure is a perspective view of a coffee urn or similar article showing my new design.

I claim:

The ornamental design for a coffee urn or similar article as shown.

CHARLES A. SCHALLIS.
